Attorney

UNITED STATES PATENT OFFICE.

FREDERICK TAYLOR, OF KAKABEKA FALLS, ONTARIO, CANADA.

ELECTRICAL WATER-HEATER.

1,320,941.

Specification of Letters Patent.

Patented Nov. 4, 1919.

Application filed April 5, 1919. Serial No. 287,744.

To all whom it may concern:

Be it known that I, FREDERICK TAYLOR, a subject of the King of Great Britain, residing at Kakabeka Falls, Province of Ontario, 5 Canada, have invented certain new and useful Improvements in Electrical Water-Heaters; and I do hereby declare that the following is a full, clear, and exact description of the invention, such as will enable 10 others skilled in the art to which it appertains to make and use the same.

The present invention relates to improvements in electrical water heaters and has for its object the provision of an improved 15 construction of this character operating to heat the water by being submerged therein, which is of simple construction, efficient in operation and capable of economical manufacture. The other objects will appear 20 hereinafter.

The invention consists in the combination and arrangement of parts hereinafter described in the claim.

The invention is best understood by reference to the accompanying drawings forming a part of this specification, and in which,

Figure 1 is a perspective view showing a heater embodying the invention in the position as used;

30 Fig. 2 is a longitudinal section of said heater; and,

Fig. 3 is an enlarged detail view illustrating one of two binding post arrangements employed in the construction.

35 The preferred form of construction as illustrated in the drawings comprises two concentric tubes 4 and 5 made of insulating material such as hard rubber, the inner tube 5 being somewhat smaller in diameter 40 and shorter in length than the outer tube 4. A heating coil 6 of resistance wire is coiled about the inner tube 5 and within the outer tube 4, the ends of said heating coil being electrically secured to suitable binding posts 45 7 arranged on the upper side and at each end of the inner tube 5. The heating coil 6 is supplied with current through the insulated wires 8 extending through suitable openings 9 in the upper side of the tube 4.

50 After passing through the openings 9 the supply wires 8 are brought together centrally above the outer tube 4 and are passed through the central opening, being a per-

forated plate 10, said wires being then twisted together at the point 11 above the 55 plate 10 to form a symmetrically arranged suspension element for the heating element.

In use the heater is simply submerged in an open vessel containing water and the electrical current is supplied through the 60 wires 8. This heats the coil 6 which in turn heats the water in the vessel, the arrangement of the tubes 4 and 5 and the coil facilitate free circulation of the water through the heating element. When the 65 water has been sufficiently heated the heating element is removed by lifting the same by means of the wires 8, said wires consisting of a symmetrically arranged suspension element for the purpose. The specific form 70 and arrangement of parts is simple in construction, efficient in operation and capable of economical manufacture.

While I have illustrated and described the preferred form of construction for carrying out my invention this is capable of variations and modifications without departing from the spirit of the invention. I therefore do not wish to be limited to the precise form and arrangement of parts disclosed, but desire to avail myself of such variations and modifications as come within the scope of the appended claim.

Having thus fully described my invention, what I claim as new and desire to secure by 85 Letters Patent is:

A water heater comprising two concentric tubes of insulating material open at both ends and the inner tube being somewhat shorter than the outer tube; binding 90 posts arranged on the upper side of said inner tube at the opposite ends thereof; a heating coil coiled around said inner tube and within said outer tube, the ends of said heating coil being connected to said binding 95 posts and there being openings in the top of said outer tube adjacent said binding posts; and supply wires secured to said binding posts and extended through said openings.

100 In witness whereof I have hereunto set my hand.

FRED. TAYLOR.
